UNITED STATES PATENT OFFICE.

FRANK COYLE, OF GRANITEVILLE, VERMONT, ASSIGNOR OF ONE-HALF TO
NELSON B. BALLARD, OF BARRE, VERMONT.

ROCK-DRILL.

SPECIFICATION forming part of Letters Patent No. 715,993, dated December 16, 1902.

Application filed February 24, 1902. Serial No. 95,249. (No model.)

To all whom it may concern:

Be it known that I, FRANK COYLE, a citizen of the United States, residing at Graniteville, in the county of Washington and State 5 of Vermont, have invented certain new and useful Improvements in Rock-Drills; and I do declare the following to be a full, clear, and exact description of the invention, such as will enable others skilled in the art to which 10 it appertains to make and use the same.

The invention relates to rock-drills, and more particularly to a chuck for the plunger of a steam, hydraulic, or pneumatic piston.

The object of the invention is to provide a 15 chuck of this character which may be readily adapted for holding a drill or reamer and which shall be simple of construction, durable in use, and comparatively inexpensive of production.

With these and other objects in view, which will readily appear as the nature of the invention is better understood, the same consists in certain novel features of construction and combination and arrangement of parts, 25 as will be hereinafter fully described, defined in the appended claims, and illustrated in the accompanying drawings, in which—

Figure 1 is a vertical sectional view of a chuck, showing it attached to the lower end 30 of the piston of a steam, hydraulic, or pneumatic drill. Fig. 2 is a top plan view.

Referring more particularly to the drawings, 1 denotes the piston of an ordinary rock-drill, provided at its lower end with a head 2, the lower face of which is tempered and the annular shoulder 3 of which is provided with a tempered collar 4, held in place by screws 5.

6 denotes the body of the chuck, having the ordinary chuck-bolt 7 and nuts 8, and 6' denotes 40 the cap for connecting the chuck-body to the piston. The cap is interiorly screw-threaded to engage the exterior threads at the upper end of the chuck-body, and a set-screw 6^a is employed to prevent the accidental unscrewing of said cap.

9 denotes a bushing arranged within the chuck-body and acted upon by the chuck-bolt and nuts to firmly secure the shank of the tool to the chuck. The tool-shank is denoted 50 by the numeral 10. The upper portion of the

chuck-body is formed with a chamber 11 to receive the head 2 of the piston, and the lower end of this piston seats upon a tempered ring 12, connected by screws 13 to the shoulder 14 of the chamber. The chuck-body is formed 55 in its side about midway its length with a transverse opening 15, and the drill-head is formed with a registering recess 16. 17 denotes a plate bolted to the chuck-body over said opening, and 18 denotes a gib movable 60 within the opening and into the recess and swiveled to the inner end of a screw 19, which works through a screw-threaded aperture 20, formed in said plate, and is provided with a jam or set nut 21.

In the class of rock-drills in which the present invention is intended for use—in drilling through a rock—means are provided for constantly rotating the piston while it is being reciprocated. It is therefore essential that 70 the chuck be locked to the piston, so that the drill-tool will be likewise rotated. By setting the gib into the recess of the piston-head and jamming the set-nut tight said chuck will be securely locked to the piston, and the piston 75 will thus be prevented from turning independently of the chuck.

From the foregoing description, taken in connection with the accompanying drawings, it is thought that the construction, operation, 80 and advantages of my improved rock-drill will be readily apparent without requiring a more extended explanation.

Various changes in the form, proportion, and the minor details of construction may be 85 resorted to without departing from the principle or sacrificing any of the advantages of this invention.

Having thus described my invention, what I claim as new, and desire to secure by Letters 90 Patent, is—

1. The combination with a piston, of a chuck, means for loosely connecting the chuck to the piston to permit of the rotary movement of one with respect to the other, means carried 95 by the chuck for fixedly clamping a tool in position, a gib, and a screw for actuating the gib and locking the chuck to the piston, substantially as set forth.

2. A chuck of the character described hav- 100

ing a transverse aperture in its wall, a plate covering said aperture, a gib slidably mounted in said aperture, and a screw working through said plate to lock the gib to or unlock it from the piston to which the chuck is adapted to be connected, substantially as described.

In testimony whereof I have hereunto set

my hand in presence of two subscribing witnesses.

FRANK COYLE.
